ELECTRIC SAFETY SWITCH

Ralph A. Millermaster, Milwaukee, Wis., assignor
to Cutler-Hammer, Inc., Milwaukee, Wis., a
corporation of Delaware

Application April 10, 1939, Serial No. 267,053

18 Claims. (Cl. 200—114)

This invention relates to improvements in electric safety switches. The invention relates more particularly to a fuseless main switch of the front-operated push-pull type.

5 A primary object of the invention is to provide an improved and simplified form of fuseless main switch of the front-operated type.

Another object is to improve the details of construction and arrangement of the parts and the 10 operation of fuseless main switches of the aforementioned type.

Another object is to provide an improved and simplified arrangement of the switch contacts with respect to branch circuit fuse socket contacts associated therewith.

15 Another object is to provide a combined push-pull fuseless main switch and branch circuit service control device having improved and simplified means for removably attaching the dead-front insulating plate within the casing.

Another object is to provide a novel form of sheet metal casing for the service control device to provide for alternative association therewith of a screw-attached cover member to adapt the 20 casing for flush mounting or a hinge-attached cover member to adapt the casing for surface mounting.

Another and more specific object is to provide 25 stationary and movable switch contacts of novel form, and a novel form of insulating actuating member for the latter.

Another object is to provide novel resilient means tending to insure movement of the insulating actuating member to one or the other 30 of its extreme positions.

Another object is to provide a service control device of the aforementioned character having means of novel form to afford grounded neutral connections.

35 Another object is to provide elements of novel form upon the casing cover and the insulating actuating member to provide for sealing of the latter in its circuit interrupting position.

Other objects and advantages of the invention 40 will hereinafter appear.

The accompanying drawings illustrate a preferred embodiment of the invention, with alternative forms of cover members to be employed with the casing; it being understood that the 45 embodiment illustrated is susceptible of modification in respect of certain details of construction thereof without departing from the spirit and scope of the appended claims.

In the drawings,

50 Figure 1 is a fragmentary top plan view of a service control device as constructed in accordance with my invention, the hinged cover member being shown in open position; and the major portion of the dead-front insulating plate being shown in dotted lines.

Fig. 2 is a fragmentary sectional view, on the line 2—2 of Fig. 1, the hinged cover being shown in closed position, and the insulating actuating member of the switch being shown in its inner extreme position to provide for interruption of the controlled branch circuits; the alternative form of cover to provide for flush mounting of the casing and the means for attaching said cover to the casing being shown by dotted lines.

5 Fig. 3 is a sectional view, on the line 3—3 of Fig. 1, with the hinged cover shown in closed position; and the alternative form of cover and certain of the attaching screws therefor being shown in dotted lines.

Fig. 4 is a sectional view, on the line 4—4 of Fig. 1, showing the insulating base and certain of the switch parts and fuse socket contacts supported thereby.

10 Fig. 5 is a perspective view of a portion of the sheet metal cover for the casing, illustrating the slotted depression in the cover and the form of the integral perforated lug which provides for sealing of the switch actuator in its circuit interrupting position, and

Fig. 6 is a perspective view of one of the insulating arc snuffing members associated with the stationary and movable contact elements of the switch.

15 Referring to the drawings, the numeral 10 designates a base adapted to be produced by a 20 straight-line molding operation from any suitable insulating material. The base 10 as shown herein is composed of unglazed gray porcelain, but it is to be understood that other insulating materials having the required strength, and insulating and heat resisting characteristics may be employed if desired. Thus I may employ a 25 molded "Bakelite" base, in which event, as is well understood by those skilled in the art, the base may be additionally recessed in various areas to 30 reduce the weight thereof while maintaining the 35 same of adequate strength.

30 Base 10 is recessed as shown at 11, said recess 35 preferably being in the form of a passage extending therethrough from front to rear. That portion of passage 11 opening to the upper surface 12 of base 10 is so dimensioned as to receive with a free sliding fit the full width portion of a flat insulating plate 13,—the lower end portion 14 of said plate being of reduced width, and the lower 40 end portion 15 of passage 11 (Fig. 3) being of similarly reduced width, while freely accommodating portion 14. Plate 13 is thus provided 45 with horizontal shoulders 16 and 17 which cooperate with the respective base shoulders 18 and 19 to positively limit the degree of inward movement of plate 13 within said passage.

50 Plate 13 is provided along its longitudinal center line (Fig. 3) with a relatively narrow slot 55 20 which extends from a point only slightly above 60

the upper surface 12 of base 10 (when plate 13 is in its inner extreme position) to a point adjacent to the lower end of portion 14 of said plate. The lower end portion 21 of slot 20 is preferably 5 slightly enlarged, as shown, to provide proper clearance for a resilient double-inclined cam member 22, the structure and function of which will be more fully described hereinafter. Extending transversely through slot 20 is a second 10 flat insulating plate 23, of the form best illustrated in Fig. 2, plate 23 having laterally extending integral lugs 24 and 25 adapted to seat within correspondingly shaped recesses in base 10.

Base 10 is provided in its upper surface with 15 recesses to accommodate the heads of a pair of bolts 26, which heads overlie the aforementioned lug portions 24 and 25 of plate 23 to clamp the latter in position, a metal washer 27 being preferably interposed between each bolt-head and its 20 associated plate lug, as shown in Fig. 2. The shanks of bolts 26 penetrate corresponding passages provided in base 10 and have threaded engagement with nuts 28 located in recesses countersunk from the lower face of base 10.

Plate 23 as thus attached to base 10 preferably has its upper edge in a plane flush with the upper surface 12 of said base, and the lower edge 29 (Fig. 2) of plate 23 is positioned for engagement by the lower end wall of portion 21 of slot 30 20 to positively limit the degree of upward movement of plate 13. As shown in Fig. 2, the aforementioned resilient double-inclined cam member 22 is provided with a hooked upper end 30 which cooperatively engages a correspondingly shaped 35 integral portion of base 10, whereby downward displacement of said cam member is prevented. The aforementioned lug 25 of plate 23 overlies said hooked end 30 of cam member 22 to prevent upward displacement of the latter; and said cam member 22 is further provided at 31 with a bend or bulge to be engaged by the side edge of plate 23, whereby bodily oscillatory movement of said cam member is prevented.

As shown in Figs. 2 and 3 the arrangement is 45 such that the portion 32 of plate 13 below portion 21 of the slot 20 is of substantially square form in transverse cross section; whereby in the relative positions of the parts as illustrated the lower portion of the double-inclined cam 22 engages 50 the left-hand upper corner or edge (Fig. 2) of said portion 32 to yieldably resist initial upward movement of plate 13. When, during upward movement of plate 13, the left-hand lower corner or edge of portion 32 passes the apex of the 55 double-inclined cam 22, the upper portion of said cam will act upon said edge to assist in effecting, or tend to effect, completion of the movement of plate 13 to its extreme upper position. Cam 22 acts in the reverse manner with respect to portion 60 32 of plate 13 to yieldably resist initial downward movement of the latter and to assist in effecting extreme downward movement thereof.

Plate 13 is provided on opposite sides of slot 20 with a pair of substantially rectangular openings 65 33 and 34 (Fig. 3) to provide for attachment to said plate of a pair of like contactors 35, preferably formed of copper strips. As best illustrated in Fig. 3 each contactor 35 has its upper or connecting portion located within and substantially spaced from the upper edge of one of said plate openings 33 or 34, whereby possible coating of the plate surfaces above the contactor will have no deleterious arc-maintaining characteristics. The arms of each contactor are 70 75 ranged on opposite faces of the plate, and the re-

duced lower end portions of said arms are bent inwardly toward each other over the respective plate shoulders 16 and 17 aforementioned. Contactors 35 are therefore constrained to move in a direction and to a degree corresponding to the direction and degree of movement of plate 13.

For cooperation with contactors 35 I provide two pairs of stationary contact elements, the elements of each pair being respectively arranged on opposite sides of plate 13. Thus as shown in Fig. 1 I provide four ledges offset inwardly from the upper surface 12 of base 10, said ledges being located in a common plane, and one pair of said ledges being better illustrated in Fig. 4. Upon one ledge of each pair is seated the flat portion 10 15 36 of a combined stationary contact and wiring terminal member, each portion 36 being secured in position by a screw 37 the shank of which passes upwardly through base 10 and through a tapped opening in said portion, and the head of which screw is accommodated in a countersink or recess in the lower face of the base. The outer extremity of portion 36 is of reduced width and is formed to provide a head 38, and portion 36 is of still further reduced width at an intermediate 20 25 point in its length to form a neck 39 (Fig. 4), which is adapted to fit rather closely between the inner side walls of a tubular steel member 40 of substantially rectangular form in transverse cross section.

As shown in Fig. 4 base 10 is recessed below neck 39 just sufficiently to accommodate the lower portion of member 40, whereby accidental displacement of the latter is prevented. Member 40 is provided in its upper end with a tapped 30 35 opening to accommodate the steel clamping screw 41 of relatively large diameter, thus providing a so-called solderless connector for one of the line wires to be associated with the switch. The solderless connector just referred to may be of the character described and claimed in my co-pending application, Serial No. 261,527, filed March 13, 1939.

Formed integrally with portion 36 and bent upwardly at substantially a right angle thereto 45 is a resilient arm 42 a portion 43 of which is offset inwardly toward plate 13 to provide a contact area, and the upper end or tip of which arm is bent or flared outwardly away from plate 13, as shown at 44 in Fig. 4.

The other stationary contact element of each pair comprises a member comprising a flat portion 45 secured to an inner ledge as by means of a screw 37 (Fig. 4) in a manner similar to the portion 36 aforementioned. Base 10 is provided in its upper surface with a pair of approximately cylindrical recesses 46 and 47 which are respectively adapted to accommodate center and screw shell fuse socket contacts, for cooperation with plug or branch circuit fuses (not shown) of usual form. Each of the center contacts of said fuse sockets comprises an integral upwardly offset extension 48 of one of the flat portions 45, base 10 being preferably provided with bosses underlying the center contacts 48 to limit the degree of inward displacement of the latter; one of said bosses being shown at 49 in Fig. 4. Formed integrally with and bent upwardly at substantially a right angle to the respective portions 45 are arms 50 having intermediate portions 51 offset inwardly toward plate 13 to provide contact areas, and outwardly bent or flared tips 52. As shown in Fig. 4 the opposed arms 42 and 50 of the respective pairs are of substantially identical form.

In order to increase the current controlling 75

capacity and the arc-snuffing characteristics of the switch mechanism I prefer to employ a pair of substantially U-shaped insulating members 53, one of which is shown in detail in Fig. 6. Members 53 may be formed of any suitable thin and flexible but relatively tough insulating material, the kind sold commercially as "fishpaper" being preferred. The opposed arms 54 and 55 of each member 53 are preferably of substantially rectangular contour, and slightly wider than the aforementioned arms 42 and 50, as best illustrated in Fig. 1. Said arms are provided adjacent to the upper ends thereof with openings 56 and 57. The contact areas and tips 43, 44 and 51, 52 are inserted inwardly and upwardly through the respective openings 56, 57, in the manner illustrated in Fig. 4, whereby the contact areas 43, 51 are exposed toward the opposite faces of plate 13, and whereby the portions 58 and 59 of said arms are positioned at the rear surfaces of the respective contact areas. The lower portions of arms 54 and 55 are therefore adapted to overlie and insulate the inner faces of arms 42 and 50 below said contact areas. Said arms 54 and 55 extend downwardly a substantial distance below the aforementioned ledges, whereby the same are adapted to accommodate therebetween one of the contactors 35 in the "off" position of the switch shown in Fig. 4. The relatively narrower connecting portions 60 of members 53 are preferably located below the aforementioned shoulders 18 and 19 (Fig. 3) on base 10, said base being recessed as shown to accommodate said connecting portions and the inwardly bent end portions of the arms of contactors 35.

The screw shell contacts 61 of the fuse sockets are preferably of identical form, each being provided with a pair of side openings like that shown at 62 in Fig. 4, whereby the same may selectively accommodate the right-hand or left-hand wiring terminal members 63, 63 of identical form, the terminal portions of which are passed outwardly therethrough prior to insertion of the binding screws 64, 64. Members 63, 63 are adapted for right-hand and left-hand assembly by a mere reversal of one thereof with respect to the other. Each member 63 includes a horse-shoe-shaped portion 65 adapted to overlie and clamp the bottom flange portion of a shell 61, as shown in Fig. 4, the portions 65 being secured to the bottom walls of recesses 46 and 47 as by means of pairs of screws 66, 66 extending upwardly through base 10. Each member 63 is provided with a pair of laterally extending lugs 67 and 68 angled in opposite directions, the upwardly angled lug 67 of the left-hand terminal and the upwardly angled lug 68 of the right-hand terminal being utilized as the usual wire guards or guides; and the downwardly angled lug 68 of the left-hand terminal and the downwardly angled lug 67 of the right-hand terminal being respectively adapted for engagement with the walls of suitable recesses in base 10 (Fig. 1) to assist in preventing lateral displacement of said terminals.

Each terminal 63 is provided with a pair of relatively small circular openings 69 and 70, base 10 being recessed below the opening 69 of the left-hand terminal and below the opening 70 in the right-hand terminal, to provide for insertion and snubbing of the bared ends of branch circuit wires to be clamped by the respective binding screws 64. Base 10 is likewise recessed to accommodate the shanks (not shown) of said screws 64.

Base 10 is provided at one end thereof with a

ledge 71 (Figs. 1 and 2) the surface of which is recessed to accommodate in a substantially flush relation a portion of a flat metal plate 72. Plate 72 is provided with a tapped opening to accommodate the relatively long shank of a bolt or screw 73 the head of which is located in a countersunk recess in the lower face of base 10; bolt 73 acting to secure plate 72 in position. A plurality of nuts 74 are threaded onto the upstanding shank of screw 73 with lugged washers 75 10 strung upon said shank below the respective nuts, to provide for attachment of the desired number of neutral circuit wires for grounding thereof. Plate 72 is provided in its outer end with an opening to freely accommodate the shank of a 15 screw 76 which extends downwardly therethrough and takes into a tapped opening in the bottom wall 77 of the sheet metal casing, designated in general by numeral 78, to provide for grounding of plate 72 and the screw 73 associated therewith.

The bottom wall 77 of casing 78 is provided adjacent to the lower end thereof with a pair of flat-bottomed projections 79 and 80 having openings (not shown) therein to accommodate the 25 shanks of suitable screws, said bottom wall 77 being also provided at the upper end thereof with a similar perforated boss 81 (Fig. 2) the opening 82 in which is enlarged as indicated at 30 83 to substantially key-hole form, to provide for downward hooking of boss 81 and opening 82 over the head and shank of a securing screw. The casing 78 may be grounded in any well known manner, as by connecting to ground an armored cable or cable containing the circuit 35 wires leading thereto and/or therefrom.

Casing 78 includes side walls 82 and 83 and end walls 84 (Fig. 2) and 85 (Fig. 3), said side and end walls being integral with the bottom wall 77. Each end wall is provided with a pair of inwardly extending flanges, such as shown at 86 in Fig. 2 and at 87 and 88 in Fig. 3; said flanges lying against the inner faces of the respective side walls and being rigidly attached thereto, as by spot-welding. Said flanges have lugs partially 43 sheared therefrom and bent outwardly at substantially right angles thereto, as shown at 89 (Fig. 2) and at 90 and 91 (Fig. 3); said lugs being located in a common plane adjacent to the open end of casing 78, and each lug having a 50 tapped opening formed therein to accommodate the shank of a cover attaching screw, when covers (not shown) adapted to provide for flush mounting of the casing are employed.

I have shown herein in full lines a cover 94 53 having a downwardly extending peripheral flange 95 for overlapping engagement with the upper portions of the side walls and end walls of casing 78. Flange 95 is provided at one side wall 83 of the casing with horizontally disposed rectangular openings to accommodate a pair of lugs 96 and 97 partially sheared from side wall 83 at the upper edge of the latter and initially bent outwardly to penetrate the aforementioned flange openings, and then bent inwardly, as best shown 60 in Fig. 3 provide a hinge connection between the cover 94 and casing 78. The side wall 82 of the casing is formed as shown at 98 (Figs. 1 and 3) and cover flange 95 is cooperatively formed as shown at 99 in Fig. 3 to provide a snap catch 70 for releasably retaining the cover in closed position. The side wall 83 is preferably provided with a pair of outwardly extending bosses 100 and 101 and the respective end walls are provided with one or more outwardly extending bosses, such as 75

shown at 102 in Fig. 2, for cooperative engagement by the cover flange 95 to insure a rather snug and non-rattling fit of the cover upon the casing.

5 Base 10 is rigidly attached to the bottom wall 77 of the casing as by means of a pair of screws 103 and 104 the heads of which are located in recesses in the upper surface of the base and the shanks of which take into tapped openings 10 in said bottom wall. The aforementioned bosses 79, 80 and 81 serve as feet to space the bottom wall of the casing a sufficient distance from the surface of the supporting wall or the like to which the complete device is attached, whereby 15 clearance is provided for the shanks of the aforementioned screws 76, 103 and 104 (Figs. 2 and 3) below said bottom wall.

The cover member 94 is provided with a depression or recess 105 having therein a slot 106 to 20 accommodate with a sliding clearance the aforementioned contactor carrying plate 13. Partially sheared and bent upwardly from cover 94 at one side of slot 106 is a lug 107 having therein an opening 108. Plate 13 is provided with an opening 109 which is adapted to register with the lug opening 108, when plate 13 is in its inner 25 extreme position, whereby the usual wire may be passed through the aligned openings and the wire ends jointly sealed, to prevent unauthorized 30 operation of the switch to circuit completing position.

As shown in Figs. 2 and 3 plate 13 is provided adjacent to its upper end with a relatively large opening 110 affording a finger grip to facilitate 35 outward pulling of said plate for circuit completion, the aforementioned depression 105 in the cover member affording a good manual grasp upon said plate. Also, as best illustrated in Fig. 3, the upper edge 111 of plate 13 is preferably 40 curved to facilitate a manual downward push thereon to disengage the contactors from the contacts.

Base 10 is preferably provided at its upper surface with an integral projection 112 (Figs. 1 45 and 2) which affords a suitable barrier between the adjacent shell contacts 61 of the fuse sockets. Base 10 is also preferably provided with a substantially cylindrical upward projection 113. Projection 113 is adapted to be rather closely 50 rounded by the circular wall of an opening 115 provided in a flat resilient insulating plate 114, the contour of which is indicated in general in dotted lines in Fig. 1, said plate overlying all of the switch contacts and wiring terminal elements of the device to provide a dead-front for 55 the latter. Plate 114 is of a width (throughout a portion of its length corresponding to the length of base 10) only slightly less than the distance between the side walls 82 and 83 of the casing; 60 whereby when plate 114 is seated against the upper surface 12 of the base, as indicated in dotted lines in Fig. 1, said side walls of the casing and the projection 113 cooperate therewith to prevent substantial movement of plate 114 in its 65 normal plane. As shown in Figs. 1 and 2, plate 114 is provided with a relatively large substantially elliptical opening 116 to provide clearance for projection 112 and to afford access to the sockets for insertion or removal of fuse plugs.

70 I provide novel means for releasably retaining plate 114 in assembled position; said means as shown preferably comprising a pair of projections 117 and 118 upon the inner surface of side wall 83. Said projections are respectively provided with 75 straight lower edges spaced upwardly from the

plane of the upper surface 12 of base 10 a distance substantially corresponding to the thickness of plate 114, whereby one side edge of said plate may be inserted or hooked thereunder. The opposite side wall 82 of the casing is provided on its inner surface with a pair of substantially hemispherical bosses 119 and 120, the lower edges of which are likewise located in a plane above the upper surface 12 of base 10 a distance substantially corresponding to the thickness of 10 plate 114. After insertion of one side edge of plate 114 beneath projections 117, 118, the other side edge thereof may be forced downwardly over projections 119, 120 and snapped beneath the lower edges of the latter, a slight degree of bending of plate 114 being necessitated for this purpose, and the same being sufficiently resilient to provide for such bending. To remove the dead-front plate 114 it is only necessary to pull or pry the same upwardly to bend the same sufficiently to provide for disengagement of the aforementioned edge thereof from the bosses 119, 120.

In practice I prefer to interpose between the bottom face of base 10 and the bottom wall 77 of the casing a relatively thin insulating plate 121 25 of fiber or the like to insure against any possible contact of the aforementioned screws 37 with said bottom wall. Plate 121 is provided with clearance openings to accommodate the aforementioned shanks of the base securing screws 103 30 and 104.

Each of the side and end walls and the bottom wall of casing 78 are provided with two or more knockouts of the triple, double or single-knockout types, certain of said knockouts being illustrated. 35

What I claim as new and desire to secure by Letters Patent is:

1. In a device of the character described, in combination, a metal casing having bottom, side and end walls and a front opening, a metal cover 40 attached to said casing for closing said front opening, a one-piece insulating base adapted to be produced by a straight-line molding operation, means for removably attaching said base to the bottom wall of said casing, the upper surface of said base being spaced inwardly a substantial distance from the open end of said casing, said base having a plurality of recesses formed therein and opening to said upper surface thereof, a plurality of pairs of center and screw shell 45 fuse socket contacts respectively located within said recesses, two of the center contacts of said fuse sockets having resilient switch contacts formed integrally therewith and arranged in a common vertical plane in laterally spaced relationship to each other, two other switch contacts carried by said base and arranged in opposed alignment with the respective switch contacts first mentioned, said base having a passage extending therethrough from front to rear, a flat plate of 50 insulating material positioned within said passage and continuously interposed between the respective pairs of opposed switch contacts, said insulating plate extending vertically upwardly from said base and projecting at all times a substantial distance beyond the open end of said casing, said cover having an opening formed therein to provide clearance for said plate during 55 vertical reciprocation of the latter, said plate having openings formed therein, a pair of sheet 60 metal contactors having connecting portions penetrating said openings and arm portions bent to lie against opposite sides of said plate, said contactors being movable jointly into and out of bridging engagement with said pairs of switch 65 70 75 75

contacts upon an outward pull or an inward push upon said plate, and the projecting upper end of said plate being formed to facilitate manual pulling or pushing thereof.

5. 2. In a device of the character described, in combination, a metal casing having bottom, side and end walls and a front opening, a metal cover attached to said casing for closing said front opening, a one-piece insulating base adapted to be produced by a straight-line molding operation, means for removably attaching said base to the bottom wall of said casing, the upper surface of said base being spaced inwardly a substantial distance from the open end of said casing, said base having a plurality of recesses formed therein and opening to said upper surface thereof, a plurality of pairs of center and screw shell fuse socket contacts respectively located within said recesses, two of the center contacts of said fuse sockets having resilient switch contacts formed integrally therewith and arranged in a common vertical plane in laterally spaced relationship to each other, two other switch contacts carried by said base and arranged in opposed alignment with the respective switch contacts first mentioned, said base having a passage extending therethrough from front to rear, a flat plate of insulating material positioned within said passage and continuously interposed between the respective pairs of opposed switch contacts, said insulating plate extending vertically upwardly from said base and projecting at all times a substantial distance beyond the open end of said casing, said cover having an opening formed therein to provide a clearance for said plate during vertical reciprocation of the latter, said plate having openings formed therein, a pair of sheet metal contactors having connecting portions penetrating said openings and arm portions bent to lie against opposite sides of said plate, said contactors being movable jointly into and out of bridging engagement with said pairs of contact portions upon an outward pull or an inward push upon said plate, the projecting upper end of said plate being formed to facilitate manual pulling or pushing thereof, said base and said plate having cooperative shoulders formed thereon to limit the degree of inward movement of the latter, said plate having a vertically extending slot formed therein, a second insulating plate extending transversely through said slot and rigidly attached to said base for cooperation with the lower end wall of said slot to limit the degree of outward movement of said plate first mentioned, and said second insulating plate cooperating with the vertical walls of said slot to assist guiding said first mentioned plate in all positions of the latter.
3. In a device of the character described, in combination, a metal casing having bottom, side and end walls and a front opening, a metal cover attached to said casing for closing said front opening, a one-piece insulating base adapted to be produced by a straight-line molding operation, means for removably attaching said base to the bottom wall of said casing, the upper surface of said base being spaced inwardly a substantial distance from the open end of said casing, said base having a plurality of recesses formed therein and opening to said upper surface thereof, a plurality of pairs of center and screw shell fuse socket contacts respectively located within said recesses, two of the center contacts of said fuse sockets having resilient switch contact arms formed integrally therewith and bent to extend upwardly at substantially right angles thereto in laterally spaced relationship to each other, two other switch contact arms carried by said base and arranged in opposed alignment with the respective switch contact arms first mentioned, the contact portions of each pair of arms being offset inwardly toward each other and the tips of said pairs of contact portions being flared apart, a pair of substantially U-shaped fiber members, the arms of said fiber members each having an opening formed therein adjacent to the upper end thereof, the tips and contact portions of said arms being insertable upwardly through said openings whereby each fiber member is interlocked with and restrained against accidental displacement relatively to each opposed pair of contact arms and whereby the lower portions of the arms of said fiber members are positioned on the inner sides of the respective contact arms to provide insulating coverings for the latter, said base having a passage extending therethrough from front to rear, a flat plate of insulating material positioned within said passage and continuously interposed between the respective pairs of opposed contact portions, said plate having a pair of openings formed therein, a pair of sheet metal contactors having connecting portions penetrating said openings and arm portions bent to lie against opposite sides of said plate, said contactors being movable jointly into and out of bridging engagement with said pairs of contact portions upon an outward pull or an inward push upon said plate, and said plate having adjacent to its upper end a finger opening to facilitate manual pulling thereof and a curved edge to facilitate manual pushing thereof.
4. In a fuseless main switch of the push-pull type, in combination, a molded insulating base having a passage of substantially rectangular contour in horizontal cross section extending vertically therethrough from front to rear, the inner end portion of said passage being of reduced dimensions whereby said base is provided with a pair of horizontal shoulders spaced from each other and from the rear surface of said base, a flat plate of insulating material of substantially greater height than said base slideable within said passage, the lower end of said plate being of reduced dimensions to provide a portion adapted to be accommodated by the reduced inner end portion of said passage and to provide spaced shoulders cooperable with said base shoulders to limit the degree of inward movement of said plate, said plate having a relatively long substantially rectangular slot formed therein at the longitudinal center line thereof and extending from a point adjacent to the lower edge thereof to a plane slightly above the upper surface of said base, when said plate is in its inner extreme position, a second flat plate of insulating material extending through the slot in said first plate and rigidly secured to said base, the lower edge of said second plate being engageable by the lower end wall of said slot to limit outward movement of said first plate relatively to said passage, said second plate also cooperating with the side walls of said slot to assist in guiding the movements of said first plate, a pair of contactors attached to said first plate on opposite sides of said longitudinal center line and having portions thereof exposed on opposite faces of said plate, two pairs of resilient stationary contacts carried by said base and into and out of bridging engagement with which the

- respective contactors are adapted to move upon outward and inward movements respectively of said first plate, and a third flat insulating plate secured to the upper surface of said base and overlying said contacts and contactors to provide a dead-front for said base, said last mentioned plate having an opening therein to provide sliding clearance for said first plate.
5. In a fuseless main switch of the push-pull type, in combination, a metal casing having bottom, side and end walls and an open front, a metal cover member for said casing, a molded insulating base member secured to the bottom wall of said casing and having a top surface offset inwardly a substantial distance from said cover member, the side walls of said casing each having bosses upon the opposed inner surfaces thereof respectively, the bosses upon one of said side walls having straight lower edges and the bosses upon the other side wall being of substantially hemispherical form, a flat plate of resilient insulating material one side edge portion of which is laterally insertable under said straight lower edges and the other side edge portion of which is forcibly insertable under said hemispherical bosses by bending of said plate by pressure applied to the upper surface thereof, said bosses acting to retain said plate flatwise against the upper surface of said base, said base having an integral portion projecting upwardly from said upper surface thereof and said plate having an opening to accommodate said projecting portion whereby said plate is restrained against substantial movement in its normal plane with respect to said base, said base having a recess opening to the upper surface thereof and said plate and said cover member having openings aligned with said recess, a flat insulating actuating plate slideable within said recess and within the openings in said cover member and said plate first mentioned, the upper portion of said actuating plate projecting at all times a substantial distance above said cover member, the lower portion of said actuating plate having a pair of contactors attached thereto, two pairs of resilient stationary contacts carried by said base, the contacts of each pair being respectively arranged on opposite sides of said recess, said actuating plate being continuously interposed between the respective contacts of said pairs, said contactors being movable by said actuating plate into and out of bridging engagement with said pairs of contacts, and means associated with said base and said actuating plate to limit the degrees of inward and outward movement of the latter.
6. In a fuseless main switch of the push-pull type, in combination, a molded insulating base having a recess opening to the upper surface thereof, said base having a plurality of pairs of ledges located in a common plane, the ledges of each pair being located respectively on opposite sides of said recess in alignment with each other, stationary switch contacts each having a portion secured to one of said ledges and an arm portion bent upwardly at substantially a right angle thereto, each pair of opposed arm portions having contact portions offset toward each other, a pair of relatively thin substantially U-shaped insulating members, the arms of each of said U-shaped members having openings spaced downwardly from the upper ends thereof, the upper ends of said contact arm portions penetrating the respective openings whereby the adjacent contact portions of the former are freed from interference by said U-shaped members, the por-

tions of the arms of said U-shaped members below said openings being adapted to overlie the adjacent faces of the lower portions of said contact arms to insulate the latter, a flat plate of insulating material vertically slideable within said recess, said plate having a pair of contactors attached thereto for movement into bridging engagement with the respective pairs of contact portions upon extreme outward movement of said plate, said contactors being also movable by said plate inwardly from said contact portions and between the insulated lower portions of said contact arms, for the purpose set forth, and said base and said plate having elements associated therewith to positively limit the degrees of outward and inward movement of the latter.

7. In a fuseless main switch of the push-pull type, in combination, a molded insulating base having a recess opening to the upper surface thereof, said base having a plurality of pairs of ledges located in a common plane, the ledges of each pair being located respectively on opposite sides of said recess in alignment with each other, stationary switch contacts each having a portion secured to one of said ledges and an arm portion bent upwardly at substantially a right angle thereto, each pair of opposed arm portions having contact portions offset toward each other, a pair of relatively thin substantially U-shaped insulating members, the arms of each of said U-shaped members having openings spaced downwardly from the upper ends thereof, the upper ends of said contact arm portions penetrating the respective openings whereby the adjacent contact portions of the former are freed from interference by said U-shaped members, the portions of the arms of said U-shaped members below said openings being adapted to overlie the adjacent faces of the lower portions of said contact arms to insulate the latter, a flat plate of insulating material vertically slideable within said recess, said plate having a pair of contactors attached thereto for movement into bridging engagement with the respective pairs of contact portions upon extreme outward movement of said plate, said contactors being also movable by said plate inwardly from said contact portions and between the insulated lower portions of said contact arms, for the purpose set forth, and said base and said plate having elements associated therewith to positively limit the degrees of outward and inward movement of the latter.

8. In a fuseless main switch of the push-pull type, in combination, a molded insulating base having a recess opening to the upper surface thereof, said base having a plurality of pairs of ledges located in a common plane, the ledges of each pair being located respectively on opposite sides of said recess in alignment with each other, stationary switch contacts each having a portion secured to one of said ledges and an arm portion bent upwardly at substantially a right angle thereto, each pair of opposed arm portions having contact portions offset toward each other, a pair of relatively thin substantially U-shaped insulating members, the arms of each of said U-shaped members having openings spaced downwardly from the upper ends thereof, the upper ends of said contact arm portions penetrating the respective openings whereby the adjacent contact portions of the former are freed from interference by said U-shaped members, the por-

ends of said contact arm portions penetrating the respective openings whereby the adjacent contact portions of the former are freed from interference by said U-shaped members, the portions of the arms of said U-shaped members below said openings being adapted to overlie the adjacent faces of the lower portions of said contact arms to insulate the latter, a flat plate of insulating material vertically slideable within said recess, 5 said plate having a pair of contactors attached thereto for movement into bridging engagement with the respective pairs of contact portions upon extreme outward movement of said plate, said contactors being also movable by said plate inwardly from said contact portions and between the insulated lower portions of said contact arms, for the purpose set forth, said base and said plate having cooperating shoulders formed thereon to limit the degree of inward movement 10 of the latter, said plate having a longitudinally extending slot formed therein, a second insulating plate extending transversely through said slot and rigidly attached to said base, the bottom wall of said slot being adapted for cooperative engagement with said second plate to limit the degree of outward movement of the plate first mentioned, said slot being spaced upwardly from the lower end of said first plate whereby a portion of the latter of substantially rectangular 15 form in transverse cross section is provided, and a resilient metal member in the form of a double-inclined cam carried by said base, said double-inclined cam cooperating with said last mentioned portion of said first plate to yieldably resist 20 initial movement of the latter from each of the extreme positions thereof and to assist in effecting final movement thereof to either of said extreme positions.

9. In a safety switch, in combination, a metal 40 casing having bottom, side and end walls and a front opening, a metal member attached to said casing for closing said front opening, a one-piece molded insulating base rigidly secured to the bottom wall of said casing, the upper surface of 45 said insulating base being spaced inwardly a substantial distance from said front opening, said base having an integral upward projection, a switch mechanism carried by said base and including stationary and movable contact members and wiring terminal elements positioned below said upper surface, the side walls of said casing having bosses formed on the inner surfaces thereof in a plane slightly above the upper surface of said base, a flat resilient insulating 50 plate having a portion of a width closely approximating the distance between said side walls of the casing and opposite end portions of a width substantially as great as the width of said base and projecting a substantial distance beyond each 55 longitudinal end of the latter, said plate being bendable to provide for movement thereof with a snap action into interlocking engagement with said bosses and into overlapping engagement with the upper surface of said base, said plate having 60 an opening to rather closely accommodate said base projection whereby substantial movement of said plate in its normal plane is positively prevented, said switch mechanism including a reciprocating insulating actuating member projecting upwardly from said base, and said plate 65 and said cover member having aligned openings formed therein through which said actuating member extends in all positions of the latter.

10. In a push-pull switch, in combination, a 70 molded insulating base having a recess formed 75

therein and opening to the upper surface thereof, a pair of ledges offset inwardly from the upper surface of said base and arranged in alinement in a common plane on opposite sides of said recess, a pair of stationary contacts having flat 5 portions secured to the respective ledges and having resilient arms bent upwardly at substantially right angles to said flat portions, said arms having alined intermediate portions offset inwardly toward each other to provide contact areas, a 10 substantially U-shaped member formed of flexible insulating material, the arms of said member having alined openings formed therein adjacent to the upper ends thereof respectively, the ends of said resilient contact arms being insertable 15 inwardly and upwardly through the respective openings whereby the portions of said U-shaped member above said openings are positioned exteriorly of said contact arms to provide for exposure of the opposed contact areas, the portions 20 of said U-shaped member below said openings being adapted to overlie the opposed lower portions of said resilient contact arms and extending downwardly a substantial distance below the latter, an actuating member comprising a flat 25 plate of insulating material reciprocable within said recess and continuously interposed between said resilient contact arms, a contactor carried by and having portions thereof exposed on opposite sides of said flat plate, said contactor being 30 movable upwardly by said plate into bridging engagement with said contact areas, and said contactor being movable downwardly by said plate out of said bridging engagement and between the lower portions of the arms of said U-shaped 35 member to provide for extinguishment of any arcs drawn between said contactor and said contact areas.

11. In a push-pull switch, in combination, a 40 molded insulating base having a recess formed 45 therein and opening to the upper surface thereof, a pair of ledges offset inwardly from the upper surface of said base and arranged in alinement in a common plane on opposite sides of said recess, a pair of stationary contacts having flat 50 portions secured to the respective ledges and having resilient arms bent upwardly at substantially right angles to said flat portions, said arms having alined intermediate portions offset inwardly toward each other to provide contact 55 areas, a substantially U-shaped member formed of flexible insulating material, the arms of said member having alined openings formed therein adjacent to the upper ends thereof respectively, the ends of said resilient contact arms being insertable inwardly and upwardly through the respective openings whereby the portions of said U-shaped member above said openings are positioned exteriorly of said contact arms to provide for exposure of the opposed contact areas, the 60 portions of said U-shaped member below said openings being adapted to overlie the opposed lower portions of said resilient contact arms and extending downwardly a substantial distance below the latter, an actuating member comprising a flat plate of insulating material reciprocable within said recess and continuously interposed between said resilient contact arms, a contactor carried by and having portions thereof exposed on opposite sides of said flat plate, 65 said contactor being movable upwardly by said plate into bridging engagement with said contact areas, said contactor being movable downwardly by said plate out of said bridging engagement, 70 said plate having a slot formed therein and ex- 75

tending longitudinally to a point adjacent to the lower end thereof, whereby a plate portion of substantially square cross section is provided, a second flat plate extending transversely through 5 said slot and rigidly attached to said base to positively limit the upward movement of said plate first mentioned, and a resilient metal member in the form of a double-inclined cam attached to said base by said plate second mentioned, said cam cooperating with the portion of said first plate of square cross section, to resist initial movement of said first plate out of each extreme position and to assist in effecting the final portion of the movement of the latter to 15 each extreme position.

12. In a fuseless main switch of the push-pull type, in combination, a metal casing having bottom, side and end walls and an open front, a metal cover member attached to said casing for 20 closing said open front, a molded insulating base member secured to the bottom wall of said casing and having a top surface offset inwardly a substantial distance from said cover member, the side walls of said casing each having bosses 25 formed upon the inner surfaces thereof in a plane a predetermined distance above the upper surface of said base, a flat resilient insulating plate having a width closely approximating the distance between said side walls of the casing 30 and a length at least as great as the length of said base, said plate being bendable to provide for movement thereof with a snap action into or out of interlocking engagement with said bosses and into or out of overlapping engagement 35 with the upper surface of said base, said base having an integral upward projection and said plate having an opening to rather closely accommodate said projection whereby substantial movement of said plate in its normal plane is 40 positively prevented, a switch mechanism carried by said base and including stationary and movable contact members and wiring terminal elements positioned below the upper surface of said base, said switch mechanism including a reciprocating insulating actuating member by which the 45 movable contact member is carried, said plate and said cover member having aligned openings formed therein through which said actuating member extends in all positions of the latter, said cover member having a perforated upright lug thereon at one side of the aforementioned opening in the former, and said actuating member having an opening adapted for alignment with said lug perforation in the inner extreme 50 position of the former, to provide for securement of said parts in a fixed relation as by means of a sealing wire of usual form.

13. In a device of the character described, in combination, a metal casing having bottom, side and end walls and a front opening, a metal cover attached to said casing for closing said front opening, a one-piece molded insulating base, means for removably attaching said base to said casing, a resilient stationary switch contact supported by said base and arranged in a vertical plane, another switch contact carried by said base and arranged in opposed alignment with the switch contact first mentioned, said base having a recess formed therein between said 70 switch contacts and opening to the upper surface thereof, a push-pull insulating member positioned within said recess and continuously interposed between the switch contacts, said member extending vertically upwardly from said base and 75 projecting at all times beyond the open end of

said casing, said cover having an opening formed therein to provide clearance for said member during vertical reciprocation of the latter, said member having an opening extending transversely therethrough, a metal contactor having a portion penetrating said opening and contact portions exposed on opposite sides of said member, said contactor being movable into and out of engagement with said switch contacts upon an outward pull or an inward push upon said member, and the projecting upper end of said member being formed to facilitate manual pulling or pushing thereof. 5

14. In a device of the character described, in combination, a metal casing having bottom, side and end walls and a front opening, a metal cover attached to said casing for closing said front opening, a one-piece molded insulating base, means for removably attaching said base to said casing, a resilient stationary switch contact supported by said base and arranged in a vertical plane, another switch contact carried by said base and arranged in opposed alignment with the switch contact first mentioned, said base having a recess formed therein between said 15 switch contacts and opening to the upper surface thereof, a push-pull insulating member positioned within said recess and continuously interposed between the switch contacts, said member extending vertically upwardly from said base and 20 projecting at all times beyond the open end of said casing, a substantially U-shaped element formed of flexible insulating material, the arms of said element having aligned openings formed therein adjacent to the upper ends thereof respectively, the ends of said resilient stationary contacts being insertable inwardly and upwardly through the respective openings whereby the portions of the arms of said element above said 25 openings are positioned exteriorly of said stationary contacts to provide for exposure of portions of the opposed inner surfaces of the latter, the portions of the arms of said element below said openings being adapted to overlie the opposed lower portions of said stationary contacts 30 and extending a substantial distance below the latter, for the purpose set forth, said cover having an opening formed therein to provide clearance for said member during vertical reciprocation of the latter, said member having an open- 35 ing extending transversely therethrough, a metal contactor having a portion penetrating said opening and contact portions exposed on opposite sides of said member, said contactor being movable into and out of engagement with said 40 switch contacts upon an outward pull or an inward push upon said member, and the projecting upper end of said member being formed to facilitate manual pulling or pushing thereof. 45

15. In a front-operated safety switch of the 50 multi-pole type, in combination, a metal casing having bottom, side and end walls and a front opening, a metal cover attached to said casing for closing said front opening, a one-piece insulating base, means for removably attaching said base 55 to said casing, a plurality of sets of fuse contacts carried by said base, one fuse contact of each set having a resilient switch contact electrically connected therewith and extending upwardly therefrom in a plane at right angles 60 thereto, a plurality of other switch contacts carried by said base and arranged in opposed alignment with the respective switch contacts first mentioned, said base having a recess formed 65 therein between said pairs of opposed switch 70 contacts. 75

contacts and opening to the upper surface thereof, a one-piece manual push-pull insulating member positioned within said recess and continuously interposed between said pairs of switch contacts, said member extending vertically upwardly from said base and projecting at all times beyond the open end of said casing, said cover having an opening formed therein to provide clearance for said member during vertical reciprocation of the latter, said member having a plurality of openings formed therein, a plurality of metal contactors having portions penetrating said openings and contact portions exposed on both sides of said member, said contactors being movable into and out of engagement with said switch contacts upon an outward manual pull or an inward manual push directly upon said member, the projecting upper end of said member being provided with a relatively large opening to facilitate such manual pulling or pushing thereof, and cooperating means carried by said insulating member and said base to positively limit the degrees of outward and inward movement of the former.

16. In a front-operated safety switch of the multi-pole type, in combination, a metal casing having bottom, side and end walls and a front opening, a metal cover attached to said casing for closing said front opening, a one-piece molded insulating base, means for removably attaching said base to said casing, said base having a plurality of substantially cylindrical recesses formed therein and opening to the upper surface thereof, center and screw shell fuse socket contacts located within each of said recesses, the center contacts of said fuse sockets having resilient switch contacts electrically connected therewith and extending upwardly therefrom in a plane at right angles thereto, other switch contacts carried by said base and arranged in opposed alignment with the switch contacts first mentioned, said base having another recess formed therein and opening to the upper surface thereof, a one-piece manual push-pull insulating member positioned within said last mentioned recess and continuously interposed between said opposed pairs of switch contacts, said member extending vertically upwardly from said base and projecting at all times beyond the open end of said casing, said cover having an opening formed therein to provide clearance for said member during vertical reciprocation of the latter, said member having a plurality of openings formed therein, metal contactors each having a portion penetrating one of said openings and contact portions exposed on opposite sides of said member, said contactors being movable into and out of bridging engagement with the respective opposed pairs of switch contacts upon an outward manual pull or an inward manual push directly upon said member, the projecting upper end of said member being formed to facilitate such manual pulling or pushing thereof, and cooperating means carried by said insulating member and said base to positively limit the degrees of outward and inward movement of the former.

17. In a fuseless main switch of the push-pull type, in combination, a sheet metal casing having bottom, side and end walls and an open front, a sheet metal cover member hinged to said casing for closing said open front, a one-piece insulating base adapted to be produced by a straight-line molding operation, said base being

rigidly secured to the bottom wall of said casing and having a top surface offset inwardly a substantial distance from said cover member, a relatively thin, flat plate of insulating material engaged with certain of said casing walls and overlying the upper surface of said base, a push-pull switch mechanism carried by said base and including a plurality of sets of stationary and movable contact members and wiring terminal elements positioned below the upper surface of said base, said switch mechanism including a reciprocating insulating actuating member by which the movable contact members are carried, said plate and said cover member having aligned openings formed therein through which said actuating member extends in all positions of the latter, a plurality of sets of fuse contacts carried by said base and respectively associated with said sets of switch contacts, said plate being formed to provide access to said fuse contacts when the former is in assembled relation to said base, said cover member having a perforated upright lug formed integrally therewith at one side of the aforementioned opening in the former, and said actuating member having an opening adapted for alignment with said lug perforation in the inner extreme position of the former, to provide for securement of said parts in a fixed relation as by means of a sealing wire or the like.

18. In a push-pull switch, in combination, a molded insulating base having a recess formed therein and opening to the upper surface thereof, a pair of ledges offset inwardly from the upper surface of said base and arranged in alignment in a common plane on opposite sides of said recess, a pair of stationary contacts having flat portions secured to the respective ledges and having resilient arms bent upwardly at substantially right angles to said flat portions, said arms having aligned intermediate portions offset inwardly toward each other to provide contact areas, a substantially U-shaped member formed of flexible insulating material, the arms of said member having aligned openings formed therein adjacent to the upper ends thereof respectively, the ends of said resilient contact arms being insertable inwardly and upwardly through the respective openings whereby the portions of said U-shaped member above said openings are positioned exteriorly of said contact arms to provide for exposure of the opposed contact areas, the portions of said U-shaped member below said openings being adapted to overlie the opposed lower portions of said resilient contact arms and extending downwardly a substantial distance below the latter, an actuating member comprising a flat plate of insulating material reciprocable within said recess and continuously interposed between said resilient contact arms, a contactor carried by and having portions thereof exposed on opposite sides of said flat plate, said contactor being movable upwardly by said plate into bridging engagement with said contact areas, said contactor being movable downwardly by said plate out of said bridging engagement, and a resilient metal member in the form of a double-inclined cam, said cam cooperating with a portion of said plate to resist initial movement of said plate out of each extreme position and to assist in effecting the final portion of the movement of the latter to each extreme position.

RALPH A. MILLERMASTER.
